UNITED STATES PATENT OFFICE

2,504,934

APPARATUS FOR AND METHOD OF
FOLDING COLLARSMutang Luke, New York, N. Y., assignor of one-
half to Kokchong Lew, New York, N. Y.

Application March 25, 1948, Serial No. 17,075

8 Claims. (Cl. 223—52.1)

1

This invention relates to means for folding or shaping shirt collars and has for its primary object the provision of a simple, sturdy and effective mechanism by which the collars of laundered shirts will be shaped or folded uniformly, speedily and effectively with a minimum of effort on the part of the operator.

At the present time, after being laundered, the collars or shirts, are shaped in two ways. The first way of shaping the collar is that known as the "stand-up" formation in which the collar has its back wall or neckband rising substantially at right angles to the plane of the body of the shirt. This disposition of the collar has certain disadvantages, one of which is the fact that the collar, arising from the body of the shirt as above described, increases the depth or bulk of the shirt, thus requiring it to consume considerable storage space not only when the shirts are packed for travelling, but when stored in the drawer of a wardrobe, or when packed in boxes for delivery by a laundry. Another disadvantage of the type of collar arrangement above described is the fact that the collar must usually be supported by an inserted cardboard strip, the placement thereof requiring time and effort on the part of the laundry employees.

The second collar arrangement and that which is generally preferred, is one in which the collar is maintained flatwise with respect to the body of the shirt, or in other words, has the neckband portion of the collar maintained flat in the same planar relation as the body of the shirt, the collar being transversely folded on divergent lines so that it lies flatly against the body of the shirt. To iron or press a collar into this position by hand operation requires skilled workmanship and the folds across the collar must not be sharply defined lest they appear boldly in the collar while it is worn. Consequently the effort and time involved to shape a collar by hand ironing into the flat form described, causes some expense and is not often resorted to by laundries. On the other hand, the formation of the collars into the flat arrangement described is very advantageous, since shirts with collars so formed can be very compactly packed and stored; the collars are not likely to become crushed or wrinkled when the shirts are stacked on top of one another; the number of boxes required for containing a very substantial number of the shirts is greatly reduced, and various other advantages are apparent to those skilled in this art.

It is, therefore, an object of the present invention to provide an apparatus by means of which

2

shirt collars may be folded and shaped into the flat formation above described without requiring skill on the part of the operator, and each collar as it emerges from the apparatus being precisely similar in shaping to that which preceded it. The invention contemplates the provision of an apparatus by means of which the shaping and folding operation can be very rapidly performed, thus reducing the expense of the shaping or folding operation very materially.

These and other objects are attained by the invention, a more particular description of which will hereinafter appear and be set forth in the claims appended hereto.

In the accompanying drawings, wherein an illustrative embodiment of the invention is disclosed—

Fig. 1 is a top plan view of a collar shaping mechanism constructed in accordance with the invention;

Fig. 2 is a side elevation of the same, with parts broken away, and other parts shown in section to disclose construction;

Fig. 3 is a front elevation of the collar portion of a shirt, showing the manner in which the collar is shaped by the improved shaping mechanism;

Fig. 4 is a view looking at the under side of the shaping mechanism;

Fig. 5 is a diagrammatic view showing how the shaping elements engage the collar of the shirt to stretch and fold the same, and

Fig. 6 is a front elevation of one of the shaping members.

Referring to the drawings, attention is directed to the fact that while certain parts of the apparatus herein shown are known in this art, such parts being shown, for example in U. S. patent to Campbell, No. 2,192,786 dated March 5, 1940, the present invention involves an apparatus and method by which a collar is shaped and folded in a manner wholly different from that disclosed in the above patent. In the drawings, 1 indicates a flat top plate, provided with a transverse groove or well 10 for the reception of a stack of shirt-securing strips or paper bands which are placed about the shirts folded by parts of the apparatus not herein shown. The top plate 1 is usually secured to or forms an extended portion of a table on which the shirt is folded, such table not being shown herein since it forms no part of the present invention and is well known in this art.

In shaping the collar according to the present invention, the shirt, which has previously been

55

ironed, and which is to be folded and banded for delivery, is placed face downwardly on the top plate 1 in such a position that the collar of the shirt will extend into the opening 11 provided in the top plate for engagement by the shaping and ironing elements located in said opening and operating in a manner to be described.

Located below the top plate 1 is a supporting member 2 in the form of a plate having flanged side edges 12 and upturned ends 3 and 4, said ends being formed with the out-turned flanges 5 secured to the top plate 1 by the bolts 6, was asbestos or similar heat-insulating material 7 interposed between the flanges 5 and the under side of the top plate 1. Fixedly mounted on the upper surface of the supporting member 2 is a stationary pressing block 13, provided with a foot portion 14, over which is positioned a reinforcing plate 15. Screws 16, extending through the foot portion 14 and the plate 15, securely attach the block 13 to the supporting member 2. Insulating material 17 is located between the foot 14 of the pressing block 13 and the upper surface of the supporting member 2. At the top, the block 13 is formed with a relatively flat integral plate portion 18, across the upper face of which the inner face of the neckband portion of the shirt collar is stretched in the act of shaping the collar. To enable the shirt collar to be properly positioned across the top 18 of the block 13, said top may be provided with a shoulder 19, or a suitable mark or other indicating element to enable the operator to quickly place the collar in the required position.

The stationary block 13 is internally electrically heated in any known manner such as by one or more thermal cartridges placed within it, the current-conducting wires therefor being shown at 20 and 21 in Fig. 4, said wires leading from a suitable electrical outlet. Ventilating openings 23 extend through the block 13, as seen in Fig. 1.

In Fig. 3 is shown a shirt which has had its collar folded or shaped in the manner in which the present invention operates on the collar. It will therein be noted that the neckband of the collar, indicated at 25 is arranged to lie in the same plane as the body of the shirt, a portion of the latter being shown at 26. This disposition of the collar is known as the "flat-folded" type and to secure this arrangement, the collar is transversely folded at the opposite sides, as indicated by the fold lines 27 and 28. While these fold lines are sufficiently defined to maintain the collar flat-wise with respect to the body of the shirt, it is desirable that the fold lines 27 and 28 be not so sharp that they will be visible as distinct creases across the collar while the shirt is being worn, but rather that they be well-rounded. For the production of these two well-rounded folds 27 and 28, triangulated shaping or folding elements shown generally at 29 and 30 are employed, and these shaping elements enter the collar and are moved apart to draw the back portion of the collar flatly across the top of the plate portion 18 of the stationary block 13, while the forward portion of the collar is being simultaneously urged in a direction to cause the inside of the collar to assume the substantially triangular form clearly shown in Fig. 3.

The shaping elements 29 and 30 are similar in shape, and each is provided with a base or foot portion 31 slidably mounted on top of the supporting member 2. Arising from the base portion 31 is a post 32 on which is the integrally-formed shaping head 33. It is to be noted that

the head 33 is provided with a rounded angular edge 34, the curvature of which is clearly seen in Fig. 1, and as the collar of the shirt is extended around and drawn smoothly about its edge it will be apparent that a well-rounded but clearly defined fold 27 or 28 will be the result. Each of the shaping members 29 and 30 is internally electrically heated, as by a thermal cartridge, the current-conducting wires leading to the cartridge for the shaper 29 being shown at 35 in Fig. 4, while the wires for the cartridge in the shaper 30 being shown at 36. A hole for ventilation is provided at 37 in each of the shaping members 29 and 30.

Secured below the base portion 31 of the shaping element 30 is a plate 37, which is located below the supporting member 2 and is attached to the base portion 31 by screws or equivalent fasteners 38 extending through a slot 39 provided in the supporting member 2. Secured on the under side of the supporting member 2 and extending transversely of the same is a grooved guide 40 in which the plate 37 is slidably mounted. Since the plate 37 is connected to the base 31 of the shaping member 30, it will be apparent that any sliding movement of the plate 37 back and forth in the guide 40 will be communicated to the shaping member 30 and the same will be thus moved to or from the block 13 according to the direction of movement of the plate 37.

At 41 is a bell-crank lever having an arm 42 pivotally engaging a stud 43 projecting from the plate 37. The bell-crank lever 41 is pivotal on a stud 44 secured in the supporting member 2 and extending downwardly from the same. The second arm indicated at 45 of the bell-crank lever 41 has its end pivotally connected to a movable bar 46, which is movable at right angles to the direction of movement of plate 47. Said movable bar 46 is guided through a central portion of the guide member 40 and also through a guiding strap 47 secured to the under side of the supporting member 2 by the bolts 48.

At one of its ends, the sliding bar 46 is provided with a rigid downward extension in the form of a bar 49 provided at its lower end with a clevis 50 in which is pivotally received the flattened end of a rod 51. Said rod 51 extends through the notched end 52 of the lug portion 53 of a bracket 54 secured to the under side of the supporting member 2 by the screws 51. The opposite end of the rod 51 is pivoted at 55 in the clevis end of an L-shaped bar 56. Bar 56 is secured at the lower end of a bar 57 which has its upper end pivoted at 58 between the ears 59 formed on and extending from a bracket 60, secured by the screws 61 to the end wall 4 of the supporting member 2. A lever 62 connects the bar 56 with suitable treadle mechanism operative in a manner to be described. A coil spring 63 surrounds the rod 51 and has one end bearing against a washer 64 located on the inside of the lug 53, and has its other end urged against nuts 65 which are threadably adjustable on the threaded portion 66 of the rod 51 to thereby regulate the tension of the spring 63.

The shaping member 29 is slidably operative in a manner similar to its companion shaping member 30. That is to say, shaping member 29 is connected to a plate 67 slidable in the guide 40, and said plate 67 carries a projecting stud 68 to which the arm 39 of a bell-crank lever 70 is pivotally attached. The second arm 71 of the bell-crank lever 70 is pivotally attached to the sliding bar 46, and the bell-crank lever is

pivoted on a stud 72 extending downwardly from the bottom of the supporting member 2.

At 73 is indicated the front or forward shaping element of the device, the same having a head portion 74 integrally formed at the upper end of a post 75 which rises from a base plate 76. The base plate 76 is secured by screws or equivalent fasteners, one of which is shown at 77, to the sliding bar 46, the screws passing through a slot 78 provided in the supporting member 2. The front shaping element 73 need not necessarily be heated, since its primary function is to stretch the collar and thereby bring the back of the collar into close contact with the top face of the plate 18 of block 13 and to cause the collar to closely conform to the edge portions 34 of the shaping members 29 and 30. If it is found advantageous to heat the front shaping element 73, the heating of the same can be done in the manner explained with respect to the shaping members 29 and 30.

The normal position of the parts is shown in Fig. 1, the position of the parts at this time being that which they occupy while ironing and shaping the collar. In other words, the parts are in their separated position and are normally maintained in that position by the pressure of the spring 63, which tends to force the slide bar 46 to the right, the bar thus carrying the front shaping element to its limit in the same direction, and also swinging the two bell-crank levers about their respective axes 44 and 72 to cause them to slide the shaping members 29 and 30 in a direction away from one another and away from the block 13.

The operation of the device is briefly as follows:

When it is desired to shape the collar of a shirt, the operator places his foot on a suitable treadle which is connected to the lever 62, and pressure on the treadle will cause the bar 57 to be swung to the left as viewed in Fig. 2, forcing rod 51 in the same direction against the pressure of the spring 63. This causes the sliding bar 46 to move to the left, which action moves the front shaping element 73 toward the forward edge of the part 18 of the block 13. At the same time the shaping members 29 and 30 are moved toward block 13, and since the tops of these members are reduced in thickness for a portion of their areas, as indicated at 80, these reduced portions can enter below the plate portion 18 of the block 13. While pressure is maintained on the treadle to retain the parts 29, 30 and 73 in their retracted position, the shirt is placed face downward, with the top of the collar engaging against the shoulder 19 on the plate 18. In placing the collar in position as above described, the collar is fitted around the shaping elements 29 and 30, and the front portion of the collar is fitted around the forward part of the front shaping element 73. As soon as the collar has been placed in position as above described, foot pressure on the treadle is released, and the spring 63 will then become effective to slide bar 46 to the right, as viewed in Fig. 2, and this will move the front shaping element 73 in the same direction and at the same time will cause the shaping members 29 and 30 to spread apart to the separated position shown in Figs. 1 and 5. This will tend to triangulate the inside opening of the collar; the back of the collar will be drawn into intimate contact with the upper face of the heated plate 18 and the collar will be drawn closely around the rounded, inclined edges 34,

of the shaping members 29 and 30, providing a well-defined but smoothly rounded fold across the collar at the two points 27 and 28. While the collar is being so shaped the folding and banding of the shirt can take place by the known elements associated with an apparatus of this kind, and then, when pressure is again applied to the treadle, the shaping elements will be slid into retracted position, allowing the shaped collar of the shirt to be easily lifted off.

The collar of the shirt treated as above described, will be found to lie relatively flat against the body of the shirt substantially as shown in Fig. 3, while at the same time, the side folds 27 and 28 formed as heretofore described not be so pronounced as to be visible when the shirt is worn. At the same time, the shirt collar, being relatively flat, will permit a large number of the shirts to be packed or stacked in small space and have other advantages apparent to those engaged in the laundry trade. By the employment of the apparatus described, the collars can be prepared in this highly advantageous manner at slight expense and in an efficient and uniform manner.

Having described one embodiment of the invention, it is obvious that the same is not to be restricted thereto but is broad enough to cover all structures coming within the scope of the annexed claims.

What I claim is:

1. An apparatus for shaping shirt collars comprising, a central support having a substantially flat upper surface over which the inside face of the back of a shirt collar is stretched, a heated shaping member located on each side of the central support and fitted within the collar, a front shaping element fitted within the collar at the front thereof, means for heating the central support and the side shaping members, and means for moving the shaping members apart and for moving the front member forwardly to thereby stretch the collar across the top of the central support and to draw it about the edges of the shaping members.

2. An apparatus for shaping shirt collars comprising, a flat-top heated support, a pair of heated slideable shapers between which the support is located, means for moving the shapers to and from the support, each of said shapers having a tapered inclined edge fitting against the inside of a shirt collar while said collar is stretched across the top of the support, the inclined edges of the pair of shapers extending divergently from the top end of the support, and a front shaper entering into the inside of the collar and tensioning the collar across the top of the support and around the inclined edges of the shapers.

3. An apparatus for shaping shirt collars comprising, a stationary heated block having a relatively flat upper face over which the inside surface of a shirt collar is placed, a plurality of heated ironing and shaping members entering inside of the shirt collar, means for causing said shaping members to be simultaneously moved toward or away from one another, so that the same, upon their movement away from one another, act to stretch the back of the collar across the top of the block and bring it into the same plane as the back of the shirt to which it is attached.

4. An apparatus for shaping shirt collars comprising, a stationary heated block having a relatively flat upper surface over which the inside surface of a shirt collar is placed, a plurality of heated ironing and shaping members entering inside of the shirt collar so placed, means for causing said members to be simultaneously

moved either toward or away from one another, so that the same, upon their movement away from one another, act to stretch the back of the collar across the top of the block and bring it into the same plane as the back of the shirt to which it is attached, one of the shaping members being movable at right angles to the others and engaging the inside front part of the collar.

5. An apparatus for shaping shirt collars comprising, a support, a heated stationary block on said support, a pair of movable heated shaping blocks, means for moving the latter blocks to and from the stationary block, each of the movable shaping blocks having a rounded, inclined outer shaping edge whereby a shirt collar placed over the top face of the stationary block and having its inside surface engaged by the movable blocks will be formed with rounded transverse folds by said edges of the blocks when the movable blocks are moved in a direction away from the stationary block, the edges of the pair of shaping blocks extending divergently from the upper end of the stationary block, and a front-engaging movable block for engaging inside of the collar at the front thereof and drawing the side portions of the collar against the edges of the other movable blocks.

6. An apparatus for shaping shirt collars comprising, a heated central support across the top face of which the inside surface of a collar is positioned, a pair of heated side blocks movable to and from the central support, said side blocks entering into the shirt collar and by their separating movement tending to draw the back of the collar across the top of the central support, a front shaper movable at right angles to the direction of movement of the side blocks, the front shaper entering into the collar at the front thereof and on its movement away from the central support tending to draw the collar snugly around the side edges of the side blocks and causing rounded transverse folds to be produced across the collar and causing the collar to be positioned flatwise with respect to the body of the shirt to which it is attached.

7. An apparatus for shaping shirt collars com-

prising, a heated central support against which the inside surface of the back of a shirt collar is positioned, a pair of triangulated shaping blocks movable to and from the sides of the central support, a front shaping block movable toward and away from the front of the central support, the several shaping blocks entering into a collar placed face downwardly on the support and stretching the collar to maintain the inside surface of the back of the collar flatwise against the heated central support and to form the opening of the collar into substantially triangular formation.

10. An apparatus for shaping shirt collars comprising, a heated central support having a flat top provided with a shoulder extending across it, a pair of heated side blocks movable toward or away from the central support, each side block having its upper end terminating on a line with said shoulder, each side block having a side edge extending angularly outwardly from the top end of the central support, a movable front shaper located forwardly of the central support and movable to or from said support, the side blocks 15 and the front shaper being simultaneously movable in a direction away from the central support while located within a shirt collar and acting to draw the inside face of the back portion of the collar flat against the top face of the central support while maintaining the top edge of the collar against the shoulder on said support.
